(57) **CLAIM**

The ornamental design for a sleeve for a shower curtain, shower curtain liner, shower curtain panel, or the like, as shown and described.

DESCRIPTION

FIG. 1 is a perspective view of a sleeve for a shower curtain, shower curtain liner, shower curtain panel, or the like according to an embodiment of my new design, shown in the environment of a shower curtain panel;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged perspective view of a portion thereof;

FIG. 9 is a front plan view thereof;

FIG. 10 is a top plan view thereof;

FIG. 11 is a bottom plan view thereof;

FIG. 12 is a left side elevation view thereof;

FIG. 13 is a right side elevation view thereof;

FIG. 14 is a perspective view of a sleeve for a shower curtain, shower curtain liner, shower curtain panel, or the like according to another embodiment of my new design, shown in the environment of a shower curtain panel;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a top plan view thereof;

FIG. 20 is a bottom plan view thereof;

FIG. 21 is an enlarged perspective view of a portion thereof;

FIG. 22 is a front plan view thereof;

FIG. 23 is a top plan view thereof;

FIG. 24 is a bottom plan view thereof;

FIG. 25 is a left side elevation view thereof; and,

FIG. 26 is a right side elevation view thereof.

All of the broken lines are directed to environment and are for illustrative purposes only. The broken lines form no part of the claimed design.
